UNITED STATES PATENT OFFICE.

ABEL C. ANTHONY, OF SAN FRANCISCO, CALIFORNIA.

TOY GUN.

1,138,529.

Specification of Letters Patent.

Patented May 4, 1915.

Application filed November 4, 1914. Serial No. 870,289.

To all whom it may concern:

Be it known that I, ABEL C. ANTHONY, a citizen of the United States, residing at San Francisco, in the county of San Francisco 5 and State of California, have invented new and useful Improvements in Toy Guns, of which the following is a specification.

An object of the invention is to provide a toy gun particularly adapted for use as 10 a souvenir or the like, and which is formed and constructed for shooting small projectiles.

The invention contemplates, among other features, the provision of a gun which can 15 be cheaply manufactured and will prove an effective toy which can readily discharge projectiles such as small sticks of wood similar to matches, or the like.

Still further objects of the invention re- 20 side in a toy which, on account of its cheap- ness of manufacture and the fact that it is preferably made of a single piece of material, provides an effective little sou-venir.

25 In the further disclosure of the invention reference is to be had to the accompanying drawings, constituting a part of this speci- fication, in which similar characters of ref- erence denote corresponding parts in all 30 the views, and in which:

Figure 1 is a perspective view of the toy gun, showing the projector in firing posi- 35 tion; Fig. 2 is a vertical longitudinal sec- tional view taken through the structure shown in Fig. 1; and Fig. 3 is a vertical transverse sectional view.

Referring more particularly to the views, I disclose a gun which is preferably made 40 of a single piece of tubular bamboo, pref- erably closed at one end, with the tubular portion forming a barrel 10. A portion 11 of the tubular barrel is cut almost entirely therefrom by slitting away a fibrous portion of the barrel toward the inner end thereof, 45 the closed end of the barrel 10 being prefer- ably formed by a knot of the bamboo and at which point the slitted portion remains integral with the barrel. This slitted portion is then bent upon itself and forms a pro- 50 jector 13. An elongated opening is formed in the tubular barrel and the free end of the projector extends therein, as shown.

Now it will be clearly seen that the portion 55 of the projector extending into the opening can be manually retreated therein, after which a projectile (not shown) such as a

match stick or a small pellet, can be placed in the opening 14 or dropped into the open end of the barrel so that it will bear against that portion of the projector lying in the 60 opening. The projector is now released and, due to the peculiar bending of the bamboo and its inherent spring-like nature, the projector will spring forward in the opening, thus discharging the pellet or projectile 65 from the barrel.

As mentioned heretofore, the entire device is formed of a single piece of bamboo which, with a knife or other suitable tool, is slit longitudinally to partially remove a surface 70 portion or sliver, leaving one end of the sliver integral with the knot end of the piece of tubular bamboo, the removed portion being then bent upon itself to form the projector extending into the opening which 75 is subsequently formed in the barrel.

From the foregoing description it will be clearly seen that the device described can be cheaply manufactured in that the entire article consists of a single piece of material; 80 that it cannot get out of order, has no metallic or other springs forming separate parts of the structure and that the spring- like action of the projector is due entirely to the inherent spring-like quality of the 85 portion of bamboo partially removed from the body or tubular barrel.

Having thus described my invention, I claim:

1. As a new article of manufacture, a gun 90 formed of a single piece of tubular material having a portion partially slit lengthwise thereof, with its inner end integral with the piece of material, said portion forming a spring-like projector and extending into 95 an opening formed in the tubular portion of the piece of material.

2. A toy gun comprising a tubular mem- 100 ber provided with an opening and a projector formed integral with said tubular member and having a portion thereof ex- tending into said opening.

3. A gun formed of a single piece of bam- 105 bo closed by a knot at one end, said bamboo being longitudinally cut to provide a por- tion partially severed from the body of the piece of bamboo and having its inner end integral with the knot end of the bamboo, said portion forming a spring-like projector operating in an opening formed in the piece 110 of bamboo.

4. A toy gun comprising a tubular mem-

ber having an opening communicating with its interior and a projector formed integrally with said tubular member by partially severing a portion of the tubular member from itself, with the free end of said projector operating in the opening and limited in its movement in the opening by the end walls thereof, said end walls forming an integral part of the tubular member.

10 5. A toy gun comprising a tubular member provided with an opening and an angular shaped spring-like projector formed integral with said tubular member and hav-

ing its free end operating in said opening, 15 with the forward and backward movement of the free end of the projector in the opening limited by transverse portions of said tubular member, said transverse portions forming the end walls of the opening. 20

In testimony whereof I affix my signature in presence of two witnesses.

ABEL C. ANTHONY.
